York, ~~etc.~~

UNITED STATES PATENT OFFICE.

JACOB R. SENSIBAR, OF CHICAGO, ILLINOIS.

METHOD OF DEPOSITING SAND.

1,392,663.

Specification of Letters Patent.

Patented Oct. 4, 1921.

Application filed September 7, 1920. Serial No. 408,492.

To all whom it may concern:

Be it known that I, JACOB R. SENSIBAR, a citizen of the United States, residing at 133 W. Washington St., Chicago, in the 5 county of Cook and State of Illinois, have invented a new and useful Improvement in the Method of Depositing Sand, of which the following is a specification.

This invention relates to the method of 10 depositing sand or the like and is fully described in the following specification and shown in the accompanying drawings in which:

Figure 1 shows the original level with 15 the first embankment thrown up;

Figs. 2, 3 and 4 show successive levels with the method of raising the embankment and applying the fabric facing thereto;

Fig. 5 is a plan view showing the method 20 of reversing the fabric; and

Fig. 6 is a perspective view of the drain pipe.

In Fig. 1, I have illustrated a vertical cross sectional view of a trench 10 which 25 is dug to form the embankment 11. A long strip of fabric 12 preferably canvas is then laid along the inner side of the embankment and over its crest. The purpose of this is to prevent erosion as the height of 30 the water rises on the embankment. A drain pipe having a vertical leg 13 and a horizontal leg 14 is placed on the ground so as to lead from a point just inside the embankment or area to be filled to a point 35 beyond what is expected to be the outer edge of the finished embankment.

As many of these drain pipes as necessary are provided and distributed around the area to be filled.

40 The drain pipe as shown in Fig. 6 is preferably made of boards and is opened at its lower or outer end, and as originally placed as shown in Fig. 1, has the vertical leg 13 open at the front except for single 45 board 15.

Water and sand are then pumped into the area in front of the embankment, 11 until the water reaches the level of the top of the board 15 when it will flow out through the 50 horizontal leg 14. This point is far enough away from the pump that the water is very calm and any sand or heavy sediment therein will gradually be deposited. This sand will eventually reach the level B of 55 Fig. 2 when it will be nearly up to the crest of the embankment 11.

A new trench 10^a is then dug in front of the old embankment 11, the sand being thrown over the top of the old embankment forming a new embankment 11^a. The front 60 of the strip of fabric 12 is now uncovered but the upper portion of this strip is held between the old embankment 11 and the material forming the new embankment 11^a. The lower part of the strip is then raised as 65 shown by dotted lines in Fig. 2 and turned so as to protect the crest of the new embankment 11^a. This new position of the strip of fabric is marked 12^a.

A new board 16 is then nailed to the front 70 of the vertical leg 13 of the drain pipe. Water and sand are again pumped in until the sand reaches the level C in Fig. 3. A new trench 10^b is then dug and the sand thrown over the top of the old embankment 75 11^a to form a new embankment 11^b and the strip of fabric 12^a is again uncovered. The lower part of this which extends between the embankments 11 and 11^a is then pulled 80 out and turned as shown in dotted lines in Fig. 3 over the top of the new embankment 11^b to form a new protecting strip 12^b. A new board 17 is then placed on the vertical leg of the drain pipe and water and sand again pumped in, until the sand reaches the 85 level D of Fig. 4.

A new trench 10^c is then dug and the sand thrown over the top of the old embankment to form a new embankment 11^c. A strip of material 12^b is again turned as previously 90 described so as to form the protecting face 12^c. This may be carried on indefinitely until the sand has reached the desired height.

The great advantage of this method is that I am able to pump sand and water into an 95 open space, deposit the sand therein and drain off the water without any danger of the sand itself being washed away.

While I have shown and described but a single embodiment of my invention it is 100 to be understood that it is capable of many modifications. Changes, therefore, in the construction and arrangement may be made which do not depart from the scope of the appended claims in which it is my invention 105 to claim all novelty inherent in my invention as broadly as possible in view of the prior art.

What I claim as new and desire to secure by Letters Patent is:

110 1. The method of depositing sand and the like which consists in forming an embank-

ment about the area to be filled, placing a strip of fabric longitudinally of the embankment, over the crest and extending down the inner side thereof to prevent it 5 from eroding, placing a plurality of drains near said embankment leading outside said area, pumping water and sand into said area, digging out the sand as the fabric becomes covered, from the inner side of the 10 strip of fabric, placing this sand on the outer face of the embankment and turning the lower edge of the strip of fabric over the newly made top of the embankment.

2. The method of depositing sand and 15 the like which consists in forming an embankment about the area to be filled, placing a strip of fabric longitudinally of the embankment, over the crest and extending down the inner side thereof to prevent it 20 from eroding, placing a plurality of drains near said embankment leading outside said area, pumping water and sand into said area, digging out the sand as the fabric becomes covered, from the inner side of the 25 strip of fabric, placing this sand on the outer face of the embankment, turning the lower edge of the strip of fabric over the

newly made top of the embankment, and raising the level of the inner end of said drain an amount substantially equal to the 30 raise in the embankment.

3. The method of forming a dike which consists in digging a trench along the inner side of the dike, piling the material so removed parallel to and adjacent the trench, placing a strip of fabric longitudinally along the inner face of the dike, digging out the sand as the fabric becomes covered, from the inner side of the strip of fabric, placing this sand on the outer face of the embankment and turning the lower edge of the strip of fabric over the newly made top of the embankment.

4. The method of depositing sand and the like which consists in forming an embankment inclosing a given area, pumping a mixture of sand and water into said area carrying a drain pipe from said area to a point outside and raising the inlet end of said pipe as the level of sand in said area is 45 raised by deposit, whereby sand is deposited in said area and water substantially free 50 from sand is drained off.

JACOB R. SENSIBAR.
